UNITED STATES PATENT OFFICE.

JAMES E. DOYLE, OF CLEVELAND, OHIO, ASSIGNOR OF ONE-HALF TO C. S. BRITTON, OF CLEVELAND, OHIO.

PRINTING-PRESS APPLIANCE.

1,222,742.

Specification of Letters Patent. Patented Apr. 17, 1917.

Application filed October 29, 1913. Serial No. 797,941.

To all whom it may concern:

Be it known that I, JAMES E. DOYLE, a citizen of the United States, residing at Cleveland, in the county of Cuyahoga, State 5 of Ohio, have invented a new and useful Improvement in Printing-Press Appliances, of which the following is a specification, the principle of the invention being herein explained, and the best mode in which I have 10 contemplated applying the principle, so as to distinguish it from other inventions.

This invention has reference to an appliance intended for attachment to that style of printing press which includes a platen and a 15 disk upon which inking rollers are intended to reciprocate. The features of the invention are associated specifically with the track and the disk according as they prescribe the positioning of one with respect to the other.

20 Until recently, in so far as I have become cognizant, no support, such as a track, has been provided for the saddles while passing over the disk to the end of relieving the soft composition rolls of undue pressure.

25 Attempts to do this have been unsatisfactory principally because the joining of such supports was not thoroughly effected, it being accomplished as economically as possible in connection with the free extremities of

30 the earlier type of track which adjoined the platen but not the inking disk. My invention provides a suitably massive bracket either integral or in precise and durable connection with the track-forming portion of

35 the frame which in the standard type borders only the platen. As such, my bracket forms a nice continuation of the track on opposite sides of the disk and itself supports on its upper end the required fountain.

40 It is furthermore awkward at present to effect the cleaning of the rollers preparatory to the application either of a different or merely fresh supply of color thereto, for the reason that they must be brought over

45 the apex of the track or in the position where neither the platen nor disk is directly underneath. My invention provides adjusting means for the separation of the disk and the laterally adjacent track into more remote

50 planes whereby the wiping or cleaning of the rollers may take place even while superposed with reference to the disk.

The inventive conception is embodied in means which are hereinafter explained and 55 variously combined in the claim, while the annexed drawing and particular description thereof together set forth in detail several

certain means constituting my invention, the disclosed means however, being but some of various mechanical forms in which the principle of my invention may be applied. 60

Directing attention to the drawing in which:—

Figure I is a side elevation of an appliance embodying my invention. 65

Fig. II is a rear elevation of the same.

Fig. III is an elevation of a modification in respect to one feature.

Fig. IV is a section on line IV IV looking in the direction of the arrows. 70

The construction constituting my appliance is wholly adapted for attachment to the upper portion of the printing press, hence only so much of the latter is represented as will indicate the conjunctive purpose of the 75 invention. The supporting frame 1 is pro-

vided on both of two opposite sides with a pair of substantially horizontal flat surfaces or pads corresponding pairs being designated as 2 and 3 respectively. The frame is 80 furthermore fashioned with forward track-forming edges which are bent obliquely upward at 4. The portion of the frame 1 adjacent the track edges 4 are formed with right-angular recesses comprising the flat surfaces 85

5 which are inclined obliquely upward and the shorter transverse surfaces 6 which terminate in the surface of the tracks 4. A carrier 7 is pivotally mounted to the frame at 8 and itself carries the two rods 9 to the ex- 90

tremities of which the saddles 10 are pivotally connected. These latter include among other things the usual pair of composition inking rolls carrying rollers 11 which are intended to travel upon the track-forming 95

edges of the frame. A more detailed description of the carrier and saddle mechanism need not be supplied since no invention is claimed as associated therewith. 100

A support 12 of approximately inverted U shape includes a pair of divergent extremities 13 adapted to lie seated upon the flat surfaces 2 as best seen in Fig. II. An interjacent portion 14 of the support 12 is provided at its own middle with an up- 105

wardly projecting boss 15 of circular cross-section having a bore 16 extending therethrough. The upper annular surface of the boss 15 is formed with four equispaced cams 17. The interjacent portion 14 is further- 110

more formed with an arched arm 18 having a curved slot 19 which should be an arc of a circle. The inking disk 20 here employed is provided underneath and centrally with a

boss 21 which is likewise of circular cross-section and of corresponding dimension as the boss 15. The under surface of the boss 21 is similarly fashioned with four equi-spaced cams 22 adapted to rest upon and cooperate with the cams 17 whereby, as will be readily understood, a rotation of the disk 20 contrives to elevate or depress the same with respect to the support 12. A thumb screw 23 extends through the opening 19 and into a suitably screw-threaded opening in the under surface of the disk 20. Through the agency of this screw, which when loosened may be slid along the slot 19, the inking disk 20 may be raised or lowered at will and furthermore fixed in various positions relative to the support 12 and incidentally to that plane of travel of the rollers 11 which is prescribed at the uppermost point of the edges 4. A pair of brackets 24 are each formed below with the inwardly extending surface 25 which are adapted to be superimposed upon the extremities 13 of the support 12. The upper ends 26 of these brackets extend rearwardly to a point beyond and above the uppermost edge of the inking disk 20 and there together support the needed fountain through the medium of fasteners 27 extending therethrough. Each of the brackets 24 is fashioned with another flat under surface or pad 28 slightly elevated and to the fore with respect to the surfaces 25. The surfaces 28 are designed to simultaneously rest upon the surfaces 3 of the frame. The upper forward edges of the brackets 24 are also of right angular construction to include surfaces 29 and 30 adapted to form a close mechanical fit with the surfaces 5 and 6 respectively as clearly seen in Fig. I. The upward extent of the surfaces 30 corresponds throughout with that of the surfaces 6 whereby the elongated upper edge 31 of the brackets may lie flush with the top surface of the edges 4 and thereby establish a smooth and very durable continuation of the tracks. The brackets 24 are screwed to the frame through the medium of bolts 32 two of which are shown to also extend through the extremities 13 to simultaneously fix these at such points. The arrangement is necessarily such that the upper surface of the inking disk 20 normally lies in substantially the same inclined plane as the plane of the inclined edges 31. It will be understood therefore that the construction of the support 12 and the brackets 24 permit of either raising or lowering the inking disk 20 with respect to the rollers 11 when they chance to be at rest thereabove, and thus another feature of practical convenience is attained.

The modification with which Figs. III and IV have to do, consists in an alternative

mode of separating the saddles from the inking disk. Such separation is again the raising or lowering of one with respect to the other. The preferred form illustrates mechanism adapted to lower the disk. According to this modification means for elevating the saddles with respect to the disk is provided in order that the rollers carried by the saddles may be rotated without friction and enable the ink to be more readily wiped from their peripheries. In this modified form the upper inclined edges of the brackets 24 are serrated to include a series of zig-zag surfaces 33 and 34 respectively. A pair of elongated track-forming members have their under edges correspondingly serrated to include a like number of zig-zag surfaces 35 and 36 respectively. The surfaces 35 are intended to normally abut the surfaces 33 while the surfaces 36 are adapted to slide on the surfaces 34. The straight upper edges 37 of these members are similarly, when in their normal position, purposed to form smooth continuations of the upper edges 4. These track-forming members are provided near their upper ends with depending ears 38 and adjacent thereto the brackets 24 have elongated and upwardly inclined slots 39 substantially parallel with the surfaces 34. Thumbscrews 40 extend through the slots 39 and suitable openings in the ears 38 whereby the upper edges 37 may be fixed so as to either lie flush with the edges 4 or rest in an elevated position. The saddles are also in the latter event necessarily elevated and the rollers 11 thereon in consequence removed from contact with the inking disk as wished.

My invention being thus described with sufficient thoroughness, what I desire to secure by Letters Patent and therefore claim specifically, is:—

A printing press appliance comprising in combination a frame formed above with tracks, a bracket structure supported thereon and having continuing track surfaces, a saddle having inking rolls adapted to be supported upon said continuing track surfaces, a support below said bracket structure, an inking disk adjustably mounted upon said support so as to permit of raising and lowering with respect thereto and means for fixing said disk in various positions of rest with respect to said track surfaces and wholly out of engagement with said rolls when the latter are positioned thereabove.

Signed by me, this 27th day of October, 1913.

JAMES E. DOYLE.
